Augustin B. Strongton

ATTORNEY

UNITED STATES PATENT OFFICE.

BRUCE FORD, OF PHILADELPHIA, PENNSYLVANIA.

STORAGE BATTERY.

1,370,011.

Specification of Letters Patent.

Patented Mar. 1, 1921.

Application filed August 23, 1919. Serial No. 319,297.

To all whom it may concern:

Be it known that I, BRUCE FORD, a citizen of the United States, and a resident of Philadelphia, in the county of Philadelphia and State of Pennsylvania, have invented certain new and useful Improvements in Storage Batteries, of which the following is a specification.

The principal objects of the present invention are, first, to improve the construction and operation of the means which support the groups of positive and negative plates and their spacers or separators in properly insulated relation; second, to cushion the plates and parts against shocks incident to transportation; third, to facilitate the use of glass jars in connection with the separate supporting of positive and negative groups of plates and their separators or spacers, and fourth, to enable the plate structure or assemblage and the supporting pedestal therefor to be handled and inserted in and removed from the jar as a unitary structure.

Other objects of the invention will appear from the following description which will be given in connection with the accompanying drawings, forming part hereof and in which—

Figure 1, is a perspective view of a plate structure including the separators, and showing at the left a pedestal strip in its normal connected position and at the right a pedestal strip detached.

Fig. 2, is a longitudinal section of the lower part of a cell.

Fig. 3 is a transverse sectional view of the same, and

Fig. 4, is a transverse sectional view showing portions of a pedestal strip, a plate, and an insulator or spacer, and illustrating a modification of the invention.

In the drawings, Figs. 1, 2 and 3, 1 is a pedestal strip and 2, are plate-feet penetrating the body of the strip. The pedestal strip may well be made of soft rubber. The term soft rubber is used in its usual sense to include soft rubber like elastic materials. The strip 1, is adherent to the feet 2, so that the plate structure or assemblage can be handled and inserted into and removed from the jar 3, as a unit. The ends of the pedestal strip may abut upon the sides of the jar while the strip rests upon the bottom of the jar and for these reasons the pedestal strip is well adapted for use in

connection with glass jars. The strips 1, are provided with sockets 4, for the reception of the plate feet or pins 2, and these sockets may be individual, as shown, or continuous, 60 like a trough as will be readily understood without further illustration. The strips are, or may be cored as indicated at 5, in order to lighten them and save material, while at the same time increasing their elasticity. 65 If of soft rubber the sockets and feet may be so proportioned as to cling to each other, otherwise they may be made adherent by the use of pitch or the like. 6 are separators or spacers arranged between the plates 70 7, and they are shown larger than the plates in order to extend beyond the edges of the plates. Only the toes of the plate-feet or pins 2, may penetrate into the body of the pedestal strips, and in that case the portion 75 of the plate-feet or pins above the strips serves to hold the bottom edges of the plates above the strips while the separators or spacers rest on top of the strips and extend below the edges of the plates. By this arrangement good separation of the plates is 80 attained.

Since the pedestal strips are, or may be elastic or resilient they serve to cushion the plates and parts against shocks such as 85 occur in handling and transportation. Each group of plates is connected by a bus-bar 8, having a terminal 9, and all the plates of a group can be supported at one side by a pedestal strip, and at the other side by a 90 terminal 9, suitably connected for that purpose with the cover of the jar.

The construction and mode of operation of the structure illustrated in Fig. 4, are the same as above described except that the 95 socket or groove element 4^a, is transferred from the pedestal strip to the foot or pin element 2^a, and the projecting element which co-operates with the socket or groove element 2^a, is formed on the pedestal strip.

I claim:

1. In a storage battery the combination of a group of plates of like polarity each having a foot, and a pedestal strip extending from plate to plate provided with a socket adherent to the feet of the plates, whereby the group of plates and the strip can be handled as a unitary structure.
2. In a storage battery the combination of a group of plates of like polarity each having a foot, and a pedestal strip provided with individual sockets adherent to the feet,

- whereby the plates and strip can be handled as a unitary structure.
3. In a storage battery the combination of a jar, plates having feet and arranged in 5 groups of like polarity, and pedestal strips extending across the plates arranged on the bottom of the jar and each provided on its top with a socket into which the feet of the plates of one group project.
- 10 4. In a storage battery the combination of a jar, plates having feet and arranged in groups of like polarity, and pedestal strips abutting on the side walls of the jar and each provided on its top with a socket 15 into which the feet of the plates of one group project.
5. In a storage battery the combination of a jar, plates having feet arranged in groups of like polarity, pedestal strips each 20 provided on its top with a socket into which the toes of the feet of one group of plates extend leaving the rest of the feet projecting above the top of the strips and spacing the bottom edges of the plates above the 25 same, and separators resting on the strips and extending below the bottom edges of the plates.
6. In a storage battery the combination of a jar, strips resting on the bottom and 30 side walls of the jar, positive plates having feet the ends of which penetrate certain of said strips, negative plates having feet the ends of which penetrate the remaining strip, the portions of said feet above the strips holding the lower edges of the plates above 35 the strips.
7. In a storage battery the combination of an elastic pedestal strip, and a group of plates of like polarity having feet penetrating the body of the strip which is adherent 40 to the feet.
8. In a storage battery the combination of a soft rubber pedestal strip, and a group of plates of like polarity having feet penetrating the body of the strip which is adherent 45 to the feet.
9. In a storage battery the combination of soft rubber pedestal strips, a group of plates having feet penetrating the body of the strips and connected with it, bus-bars 50 connecting the plates, and separators between the plates and the strips and the bus-bars, whereby the parts constitute a unitary plate structure, substantially as described.
10. In a storage battery the combination 55 of elastic pedestal strips, a group of plates having feet penetrating the body of the strips and connected with it, bus-bars connecting the plates, and separators between the plates and the strips and bus-bars, 60 whereby the parts constitute a unitary plate structure, substantially as described.

BRUCE FORD.
